CROWN BLOCK

Harry P. Wickersham, Huntington Park, and
Erwin Burns, Los Angeles, Calif.

Application August 7, 1935, Serial No. 35,107

4 Claims. (Cl. 254—190)

This invention has to do with hoisting equipment and has particular reference to a crown block for use on a well derrick. A general object of this invention is to provide a simple, sturdy and compact crown block.

The crown blocks employed on the derricks of oil wells and gas wells are usually quite complicated structures embodying a large number of separable parts. For example, a typical crown block includes, in addition to the shafts and sheaves, separable bearings for the shafts, spacers on the shafts between the sheaves, spacer plates, tie rods, beams or supports, etc. The inclusion of these many parts makes the typical crown blocks very expensive and, of course, adds to their size and weight.

Another object of this invention is to provide a crown block that embodies a minimum number of parts and is, therefore, simple and inexpensive.

Another object of this invention is to provide a crown block that embodies a simple, one piece or integral body for carrying a plurality of sheave supporting shafts.

Another object of this invention is to provide a crown block embodying a unitary base or body structure having spaced supports or beam parts for carrying the shafts whereby the shaft of each individual sheave may be supported on two spaced beam parts.

Another object of this invention is to provide a crown block of the character mentioned embodying a plurality of sheaves spaced and grouped to properly handle the cables or lines.

Another object of this invention is to provide a crown block that embodies a simple effective cover or guard that extends over and shields the several sheaves and prevents the lines from escaping or jumping from the sheaves.

The various objects and features of our invention will be fully understood from the following detailed description of typical preferred forms and applications of our invention, throughout which description reference is made to the accompanying drawing, in which:

Fig. 1 is a side elevation of the improved crown block of this invention. Fig. 2 is a top or plan view of the crown block with the guard removed and Fig. 3 is a transverse detailed sectional view of the crown block taken in the plane of the central sheave.

The improved crown block provided by our present invention includes, generally a body 10, a plurality of sheaves 11 mounted on the body 10, and a cover or guard 12 on the body for shielding the sheaves.

The body 10 is in the nature of a frame for carrying the several sheaves 11 and is adapted to be mounted or arranged on the head or water table of a well derrick. The construction and formation of the body 10 are important features of the invention. In accordance with the invention the frame or body 10 is a unitary or one-piece casting or member. The body 10 is a substantially rectangular box-like structure comprising spaced vertical sides 13 and spaced vertical ends 14 extending between and integrally joining the sides. The sides 13 of the body 10 have the configuration of I beams, being provided with base flanges 15 and top flanges 16 projecting horizontally in both directions from their bodies or 10 webs. The sides 13 project or extend outwardly beyond the opposite ends 14 to have wing extensions or wings 17. The base flanges 15 of the wings 17 may be thickened to rest on supports of the derrick to carry the crown block. The outer edges or ends of the wings 17 are preferably flanged and are inclined or curved downwardly and outwardly as clearly shown in Fig. 1 of the drawing. The body ends 14 have top flanges 18 in the same plane as the top flanges 16 of the sides, the upper surfaces of the flanges 16 and 18 preferably forming continuous regular horizontal faces or surfaces. Outwardly projecting flanges 19 extend along the lower edges of the ends 14 and their opposite ends join the inner 30 base flanges 15 of the wings 17.

In accordance with the invention a plurality of spaced beam parts or sheave supporting partitions 20 extend across the interior of the body 10. The beam parts or partitions 20 are integral parts of the unitary body 10. The number and the relative positions of the partitions 20 depend to a large extent upon the number and character of the sheaves embodied in the crown block. In the typical form of the invention shown in the drawing there are two sheave supporting partitions 20. The beam parts or partitions 20 are vertical and extend between the body ends 14 being integrally joined with the ends. The partitions 20 may be of the same cross sectional configuration as the sides 13 having base flanges 21 and top flanges 22. The upper surfaces of the top flanges 22 are preferably in the same horizontal plane as the upper surface of the flanges 16 and 18. The compartment or space between the two partitions 20 may be of the same width as the spaces between the partitions and the adjacent sides 13. The lower end of the body 10 is open, that is, the lower end of the body is open between the base flanges 21 of the partitions 20 55

and between the base flanges 21 and the flanges 15 of the adjacent sides 13. The upper ends of the sides 13 and the partitions 20 are formed with recesses or seats for carrying the sheave supporting shafts as will be hereinafter described. It is to be noted that the body 10 just described is a simple one-piece structure having a high degree of strength and rigidity for the parts and material involved.

10 The sheaves 11 are provided to carry or handle the lines employed in the well derrick. The number and relative sizes of the sheaves 11 may depend upon the requirements of the particular use or installation of the crown block. In the form 15 of the invention shown in the drawing there are five sheaves 11 of equal effective diameter. In the arrangement or relative disposition of the sheaves illustrated there is a central sheave 11 supported on the two partitions 20 and two 20 sheaves 11 supported on each side 13 and the adjacent partition 20. The sheaves 11 comprise suitable hubs 23, bodies or webs 24 and rims 25 having tapered grooves 26 for receiving the cables or lines.

25 The means for rotatably supporting the sheaves 11 include shafts 27 and bearings 28 rotatably supporting the sheaves on the shafts. The sheaves 11 are rotatable about axes disposed transverse of the sides 13 and partitions 30 20 and the axes of rotation of the outer sheaves 11 are aligned, that is, the axes of rotation of the spaced sheaves 11 at one side of the block are aligned with the axes of the corresponding sheaves 11 at the other side of the block. Partially cylindrical grooves or bearing seats 29 are provided in the upper sides or flanges 16 and 22 of the sides 13 and partitions 20 for receiving the end portions of the shafts 27. The flanges 22 of the partitions 20 have elevated or upwardly extending portions 30 provided with bearing seats 29 for carrying the shaft 27 of the central sheave 11. The top flanges 16 and 22 and the portions 30 are preferably thickened adjacent the seats 29. Vertical thrust rims or flanges 31 are provided 45 at the seats 29 to receive end thrusts from the hubs 23 and the bearings 28. In the preferred construction the end portions of the shafts 27 received in the seats 29 are of reduced diameter leaving or providing intermediate portions 32 of 50 larger diameter for carrying the anti-friction bearings 28. The ends of the enlarged portions 32 of the shafts are adapted to cooperate with the thrust flanges 31 to limit the endwise movement 55 of the shafts. Suitable caps 33 are bolted or otherwise secured to the flanges 16 and 22 and the portions 30 to retain the shafts 27 on the seats 29. The caps 33 preferably have thrust flanges 34 similar to the thrust flanges 31. The invention provides lubricant ports 35 in the shafts 27. The ports 35 extend from the outer ends of the shafts to the bearings 28 and lubricant receiving fittings 36 are provided at the outer ends of the ports whereby grease or other lubricant may be readily supplied to the bearings 28.

60 The cover or guard 12 is provided to protect the sheaves 11 and to prevent the lines from jumping or escaping from the sheaves. In accordance with the invention the guard 12 is a simple one-piece member extending between the flanges 18 of the body ends 14. In the construction illustrated the guard 12 is arched or curved to pass above the several sheaves 11 with desirable clearance, it being understood that the shape

of the guard 12 may be varied somewhat to accomodate sheaves of different diameters and arrangement. Downwardly projecting inclined lips 40 may be provided on the outer top flanges 18 of the ends 14 and the edge or end portions of 5 the guard 12 may be secured to these lips by bolts or screws 41. In accordance with the invention the guard 12 passes over the sheaves 11 in relatively close proximity to their upper peripheral portions to prevent the lines from jumping or 10 escaping from the grooves 26. The central sheave 11 having its axis of rotation spaced above the axes of rotation of the other sheaves 11 has its upper peripheral portion adjacent the inner side of the guard 12 so that the guard arched as described above is effective in preventing the escape of the line from the center sheave as well as the other sheaves.

15 It is believed that the utility and practicability of the crown block of the present invention will 20 be readily apparent from the foregoing detailed description. The crown block of the invention is particularly simple embodying only the integral body 10 and the guard 12 in addition to the sheaves and their shafts. The integral or one- 25 piece body 10 constitutes the base or frame of the crown block and carries the individual shafts 27 of the several sheaves 11. The body 10 may be 30 readily mounted and secured on the head or water table of the derrick, its wings 17 constituting simple effective mounting parts. As the sheaves 11 are carried for rotation by the anti-friction bearings 28 the shafts 27 do not rotate and the body seats 29 are not worn. The sheaves 11 are spaced and related for the proper handling of 35 the lines and the body 10 is such that the sheaves may be arranged in a small compact group. The sheave supporting shafts 27 supported as described above are dependably carried on the beam like sides 13 and partitions 20 of the body. The 40 lines passing over the sheaves 11 are free to pass downwardly through the spaces between the base flanges 15 and 21. The simple cover or guard 12 in addition to effectively shielding the sheaves 11 prevents the escape of the lines from the sheaves. 45 The enlarged portions 32 of the shafts 27 provide extensive surfaces for the bearings 29 and operate to limit endwise movement of the shafts. The supporting or mounting of the sheaves 11 embodies a minimum number of simple dependable parts. The box like body 11 having the partitions 20 extending through its interior is very 50 rigid and strong.

55 Having described only a typical preferred form and application of our invention, we do not wish to be limited or restricted to the specific details herein set forth, but wish to reserve to ourselves any variations or modifications that may appear to those skilled in the art or fall within the scope 60 of the following claims:

Having described our invention, we claim:

1. A crown block including a frame, a substantially centrally disposed shaft carried by the frame, outer shafts carried by the frame at points spaced below and outwardly from the first mentioned shaft, sheaves on the shafts, and an arched guard on the frame extending over the sheaves in relatively close proximity to their rims to prevent the escape of lines from the sheaves. 70
2. In a crown block, an integral body comprising spaced sides, spaced ends connecting the sides, and spaced parts extending between the ends, elevated bearing seats on the spaced parts, a shaft carried in the seats, aligned bearing seats on the 75

sides and the adjacent parts, shafts carried in the last named seats, and sheaves on the shafts.

3. A crown block including an integral body comprising spaced ends, spaced sides connecting the ends, and partition parts extending across the interior of the body, shafts supported on the sides and said parts, sheaves on the shafts, and integral thrust flanges on the sides and parts to limit endwise movement of the sheaves.

10 4. A crown block including an integral body

comprising spaced ends, spaced sides connecting the ends, and partition parts extending across the interior of the body, shafts having their end portions supported by the sides and parts and having intermediate portions of enlarged diameter, sheaves rotatably supported on the enlarged portions, and integral thrust flanges on the sides and parts engageable by said enlarged portions.

ERWIN BURNS.
